Specification for Design.

Patented Aug. 10, 1920.

Application filed February 9, 1920. Serial No. 357,367. Term of patent 14 years.

To all whom it may concern:

Be it known that I, JOHN H. LICKERT, a citizen of the United States, residing at Evanston, in the county of Cook and State of Illinois, have invented a new, original and ornamental Design for a Combination Cleaver, Perforator, and Ice-Pick, of which the following is a specification, reference being had to the accompanying drawing, forming a part thereof.

The drawing shows a plan view and a side elevation view of a combination cleaver, perforator and ice pick, showing my new design.

I claim:

The ornamental design for a combination cleaver, perforator, and ice pick, as shown.

JOHN H. LICKERT.
